UNITED STATES PATENT OFFICE.

CLAI'RE H. EDDY, OF CLEVELAND, OHIO.

DESIGN FOR AN ADVERTISING CABINET.

Application filed September 9, 1927. Serial No. 23,334. Term of patent 3½ years.

To all whom it may concern:

Be it known that I, CLAI'RE H. EDDY, a citizen of the United States, residing at Cleveland, in the county of Cuyahoga and State of Ohio, have invented a new, original, and ornamental Design for Advertising Cabinets, of which the following is a specification, reference being had to the accompanying drawing, forming part thereof.

Fig. 1 is a front elevational view and Fig. 2 is a rear elevational view of an advertising cabinet, showing my new design. Fig. 3 is a fragmentary side view of Fig. 1.

I claim:

The ornamental design for an advertising cabinet, as shown.

CLAI'RE H. EDDY.
